UNITED STATES PATENT OFFICE

2,445,050

CLINKER OVEN

Don H. Wilhite, Kirksville, Mo., assignor to
Ralph Eggert, Adair County, Mo.

Application August 28, 1946, Serial No. 693,422

11 Claims. (Cl. 126—242)

1

The present invention relates to clinker ovens, and is particularly concerned with an improved device by means of which clinkers may be removed from stoker fired furnaces of all kinds and left to cool in such manner that the obnoxious gases are carried away by the natural draft of the furnace.

One of the objects of the invention is to provide an improved attachment for stoker fired furnaces which is adapted to be used upon practically all of the different types of furnaces on the market by being substituted for the firing door and hung upon the same hinge lugs from which this door may be removed, and by means of which the clinkers may be removed through the firing door and placed in this device for cooling to a condition which no longer involves the high temperatures or obnoxious gases which are present when the clinker is first removed.

Another object of the invention is to provide an improved device of the class described which is so arranged that it may be used when a front stoker installation without any of the parts of the device interfering with the feed tube or other parts of the stoker.

Another object of the invention is to provide an improved clinker oven structure, the upper part of which is so arranged that the clinkers in the fire pot are still in full view, and so that they are readily accessible through the opening in the clinker oven.

Another object of the invention is to provide an improved clinker oven which may be arranged with its ash drawer for right-hand or left-hand removal, and which is so arranged that the ash drawer chamber is automatically kept clean, all ashes and parts of the clinker falling into the removable ash drawer.

Another object of the invention is to provide an improved clinker oven for stoker fired furnaces of all kinds, which is sturdy, simple in structure, efficient, and adapted to be manufactured at a very low cost, so that it may be sold at a price which is within the range of a large number of the purchasing public.

Other objects and advantages of the invention will be apparent from the following description and the accompanying drawings, in which similar characters of reference indicate similar parts throughout the several views.

Referring to the drawings, of which there are two sheets,

Fig. 1 is a side elevational view of a stoker fired furnace provided with a clinker oven embodying the invention.

2

Fig. 2 is a fragmentary side elevational view on a larger scale, with certain of the parts in partial section to show the details of structure.

Fig. 3 is a front elevational view of the clinker oven attachment with parts of the housing broken away to show the internal structure.

Fig. 4 is a horizontal sectional view taken on the plane of the line 4—4 of Fig. 3 looking in the direction of the arrows.

Fig. 5 is a fragmentary sectional view taken on the plane of the line 5—5 of Fig. 3 looking in the direction of the arrows, and showing the details of structure of the hinge door stop for the upper or connecting section of the oven.

15 Referring to Fig. 1, this is a diagrammatic view showing the complete installation in which 10 indicates generally the stoker fired furnace, 11 the stoker, and 12 the feed tube from the stoker to the furnace in a front fired installation. 13 indicates in its entirety the clinker oven, which preferably comprises an upper or connecting section 14 and a lower or clinker receiving housing 15.

20 The housing 15 preferably comprises a rectangular sided sheet metal housing which is provided with a door 16 at one end. The housing 15 preferably has an open top which is bordered by an inwardly projecting flange 17 or a top wall 17 having a rectangular opening 18. The rectangular opening 18 is small enough so that the flange 17 of the top wall overlies the ash drawer 19 to prevent ashes or clinker parts from falling between the ash drawer 19 and the housing 15. Aperture 18 is preferably rectangular in shape, but smaller than the top opening area of the ash drawer.

25 In addition to the open top wall 17, the housing 15 comprises a pair of side walls 20, 21, and end wall 22, and a bottom wall 23. In some embodiments of the invention the top wall 17 may be formed by bending over parts of the side and end walls, and three of the walls, such as the rear wall 20, bottom wall 23, and front wall 21, may consist of one integral piece bent into proper shape. In other embodiments of the invention all of these walls, 17, 20, 21, 22, may consist of separate pieces of sheet metal, such as steel, which are welded together at their corners to provide a substantially air-tight compartment.

30 45 50 55 The top wall 17 of the lower housing 15 may be formed by the lower portion of a U-shaped member which forms the upper connecting portion 14. Such a U-shaped member may include, beside the bottom portion 17 of the U, a pair of

side wall portions 24, 25 (Fig. 3) and a narrow top wall portion 26.

The top wall 17 is formed by the base of the U-shaped portion and has a portion 23 projecting horizontally beyond lower housing 15 into engagement with the door opening for the firing door, and forming the lower side of the connecting portion 14 from the firing door to the ash housing 15.

The side wall portions 24, 25 are provided with beveled edges 27 extending from the forward lower corner 28 of the connecting portion 14 of the housing to the upper corner 29 adjacent the fire door opening, and these beveled edges are engaged by a suitable door 30 which may be hinged to the side wall 25. The opening for the door 30 may be framed by the top member 26, side walls 24 and 25, and at its lower edge by a special V-shaped angle member 31 which may, in some embodiments of the invention, be turned up and form an integral part of the wall 17.

The door 30 preferably comprises a substantially rectangular metal member which is provided with hinge lugs 32, 33, projecting from its right-hand edge, and provided with apertures for receiving the hinge pintle 34. The side wall 25 of the upper housing portion 14 is also provided with outwardly projecting hinge lugs 35, 36, suitably located to engage the lower sides of the hinge lugs 32, 33, and provided with registering apertures for the pintle rod 34.

The hinge lugs 32, 33 are welded to cover 30, while hinge lugs 35, 36 are welded to side wall 25, and the lugs may be provided with a lateral extension having an upper stop surface 37 in each case for engaging the door 30 and holding it in open position.

Pintle rod 34 may consist of a cylindrical steel rod of suitable size having a laterally turned upper end 38 serving as a thrust member to determine the final position of the rod in the hinge lugs. At its left end the door 30 is preferably provided with a suitable pivoted latch 39. This latch may consist of a strap of steel pivotally mounted at 40 on the cover 30 by means of a rivet, and having its end projecting beyond the cover to engage a keeper 41. A handle strap 42 is preferably bent to U-shape, and has its attaching flanges riveted to the latch strap 39.

A stop member 43 for the latch may also be of substantially U-shape, and may pass through the handle strap 42 and have its attaching flanges riveted to the cover 30 at each end 44. The keeper 41 may consist of a strap of steel, which has one side welded to the side 24, and which projects outwardly beyond the adjacent edge of the cover 30.

Just beyond the beveled edge 27 of the side wall 24 the keeper 41 is provided with a rectangular slot 45, the outer wall of which serves as a retaining shoulder for engaging the latch 39.

The operation of the latch will be apparent from its structure, as it is urged into latching position by gravity, and it may be unlatched by lifting on the handle 42.

The lower housing 15 is preferably provided with an inwardly turned flange 46 surrounding the upper opening 18. Flange 46 and flange 17 are provided with a plurality of regularly spaced apertures, such as an aperture at each corner, for receiving screw bolts 47 having nuts 48, by means of which the lower housing 15 is hung from the upper or connecting housing 14.

The present clinker oven is preferably so constructed that it may replace the ordinary firing

door on the furnace on which it is intended to be used. For this purpose the rear opening 49 in the upper housing 14 is preferably of the same size as the opening for the firing door. Thus the edge of the opening 49 engages the firing door opening on the furnace in the same manner as the firing door.

In order to provide for the support of the assembly on the firing door hinges the upper housing 10 is provided with a pair of hinge lugs 50 welded to the side wall 22 adjacent the opening 49, and provided with aligned apertures 51 for receiving a pintle rod similar to the pintle rod 34, this being the pintle rod which formerly supported the firing door.

The lugs 50 may then engage similar hinge lugs on the firing door frame of the furnace 10, and the attachment is pivotally supported in the same way that the firing door was before its removal. At its side opposite to the hinge lugs 50 the side wall 24 is provided with a short angle member 52 welded to the side wall and projecting far enough to engage the keeper 53 carried by the wall of the furnace 10. In this case the looseness of the pivotal support at the hinge lugs 50 is sufficient to permit the whole assembly to be lifted slightly at its left side until the latch 52 engages the keeper 53 on the firing door frame.

Instead of being supported on the floor, as in some of the devices of the prior art, the ash housing 15 is thus carried from the connecting portion 14 of the housing, and may be short enough to clear the coal feed tube 12 from a front stoker installation.

Ash housing 15 is also provided with a door 16 at one end, and this door is provided with hinge lugs 54 having apertures for receiving pintles 55, which also pass through the hinge lugs 56 on the front wall 21 of the lower housing 15. In this case the pintles 55 are riveted in place, but may also consist of one single pintle rod 34, if desired.

The ash housing door 16 may be provided with a latch 57 at its left side (Fig. 2), and a rear wall 20 with a keeper 58 for engagement with the latch 57. In this case the latch 57 may be pivotally mounted upon an angular bracket 59, and may have a groove 60 for engagement with the keeper 58 carried by the rear wall 20. Thence the lower section 15 is supported by bolts and nuts 47, 48 on the upper housing 14. It will be apparent that it may be attached with the door 16 opening toward the left side of the furnace or the right side of the furnace, whichever location is most desirable from the point of view of removal of the drawer 19.

The clinker drawer 19 may consist of a sheet metal member preferably constructed of sheet steel of suitable gauge, like all of the other housing members and doors. Clinker drawer 19 comprises a bottom 61, front and rear walls 62, 63, and end walls 64, 65. The end wall 64, which faces the opening closed by the door 16, is preferably provided with a handle 65a, which may consist of a U-shaped member having its laterally turned ends pivotally mounted in lugs 66 carried by the end wall 64. Thus handle 65 swings downward when not needed, and enables the use of the full space in the housing 15 for the clinker drawer 19.

In order to carry the clinker drawer 19 once it has been removed by means of the handle 65, it is preferably provided with a bail 67 which may consist of a U-shaped steel rod having its outwardly turned ends 68 pivotally mounted in aper-

tures in the side walls 62, 63 of the clinker drawer 19. The legs of the U-shaped bail 67 spring outward to retain the trunnions 68 in their apertures in the drawer, and the apertures are preferably located near the top edge and midway between the ends of the drawer to achieve a balance. In some embodiments of the invention a pair of bails may be used.

The length of the legs of the bail 67 is preferably such that the bail tips over into engagement with the end wall 64 adjacent its upper edge, as shown in Fig. 3, but beneath the flange 17, so that the bail does not interfere with the dropping clinkers.

The sides and bottom of the clinker drawer 19 are welded together at their edges, and may be formed out of one or more pieces, as desired.

In order to protect the door 30 of the upper housing 14 from heat it is preferably provided with a baffle plate 69 similar to the baffle plates usually employed upon the firing door. This may consist of a plate of sheet metal, such as steel, which is spaced from the door 30 by tubular sleeves 70 carried by the bolts 71, which may be located at each of the corners of the baffle plate.

Baffle plate 69 may have suitable apertures which are staggered with respect to the damper openings 72 in the door 30, which are adapted to be closed by means of a suitable sliding damper 73 actuated by a knob 74 carried by a bolt extending through a slot 75. The damper openings 72 and damper 73 may be similar to that employed on the firing door which this attachment is intended to replace.

The operation of my clinker oven is as follows: The firing door upon the furnace 10 may be removed and the same pintle rod utilized for securing the present attachment in its place. The attachment is then swung around until its latch 52 engages the keeper 53 on the furnace, in which position the edges of the upper housing 14 engage the edges of the firing door opening quite closely to effect a substantial closure. However, the closure can be made air-tight by means of suitable initially plastic furnace cement, and thus the leakage of air at this point can be reduced to a minimum. This is of importance when the stoker 11 is actually going, and the forced air feed causes an increase of pressure inside the furnace which might otherwise result in the smoke leaking out through the connection between the clinker oven and the furnace.

When the furnace is to be serviced and clinkers or ash removed, the door 30 may then be opened, and on account of the bevel of the upper edges 21 of the side walls 24 and 25, a full view of the interior of the furnace is permitted, and the operator may reach in with his clinker tongs in substantially the same manner as he could before the attachment was placed on the furnace.

While this is being done, the door 30 is supported in its open position upon the door stops 31, and the clinker may be drawn out of the firing door into the upper housing section 14 and dropped immediately into the clinker drawer 19 through the opening 18. If necessary, the clinker can, of course, be broken up, but any clinker which would pass the fire door before may still be handled by the present clinker oven without breaking, as the full area of the firing door is available for clinker removal. In any event, should the clinker be too large to pass through the opening 18, it may be broken at that point

by a few blows with the clinker tongs, causing it to drop into the clinker drawer 19.

When ash is removed, a shovel or suitable tool may be employed, and the ash need only be moved as far as the opening 18 when it may be dropped immediately into the ash or clinker drawer 19 without any of it falling upon the floor. When the clinkers and ash have been removed, the door is then closed, and the clinkers and ash are preferably left there to cool until the next cleaning operation, when the door 16 may be opened for removal of the clinker from the lower housing 15.

The device is preferably made of relatively heavy gauge steel, adapted to withstand the heat of the clinkers without substantial damage or deformation. While the clinker is cooling, the gases which pass off from it are drawn into the furnace by the natural draft which takes place between operations of the stoker, air finding its way into the space surrounding the clinker through the leakage of the doors. In any event, such gases tend to pass upward out of the opening 18 and into the fire door, and the amount of smoke or gas escaping into the room is reduced to a minimum.

To remove the drawer it is only necessary to lift the latch 57 and then to pull upon the drawer handle 65 until the bail 67 is accessible.

The clinker now having cooled, the entire assembly will be cool, and the bail may be grasped and used for carrying the clinker drawer outside, to be emptied at any suitable point.

In some embodiments of the invention the device may be provided with a pair of drawers, one being available to replace the other immediately, so that it is not necessary to empty the drawer before placing clinkers in the oven.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States is:

1. A furnace installation comprising a furnace having a firing door opening surrounded by a frame, hinge means carried by said frame, and a clinker disposal unit, said unit being provided with complementary hinge means for engaging said frame hinge means to pivotally secure said unit to the frame and enable said unit to be swung away from said opening and comprising an upper housing section and a lower housing section, the lower housing section being provided with an upper opening communicating with the upper housing section, and the upper housing section being provided with a door on its forward side for access to both the fire door opening and the lower housing section, whereby a clinker or the like may be removed from the furnace and dropped into the lower housing section.

2. A furnace installation comprising a furnace having a firing door opening surrounded by a frame, hinge means carried by said frame, and a clinker disposal unit, said unit being provided with complementary hinge means for engaging the fire door frame and comprising an upper housing section and a lower housing section, the lower housing section being provided with an upper opening communicating with the upper housing section, and the upper housing section

being provided with a door on its forward side for access to both the fire door opening and the lower housing section, whereby a clinker or the like may be removed from the furnace and dropped into the lower housing section, said upper housing section having its door opening and door arranged to extend diagonally from a point adjacent the top of the fire door opening to a point adjacent the lower housing section.

3. A furnace installation comprising a furnace having a firing door opening surrounded by a frame, hinge means carried by said frame, and a clinker disposal unit, said unit being provided with complementary hinge means for engaging the fire door frame and comprising an upper housing section and a lower housing section, the lower housing section being provided with an upper opening communicating with the upper housing section, and the upper housing section being provided with a door on its forward side for access to both the fire door opening and the lower housing section, whereby a clinker or the like may be removed from the furnace and dropped into the lower housing section, said lower housing section being provided with a clinker receiving drawer and having a door opening and door for removal of the drawer when the clinker has cooled, the said lower housing section being removable from the upper housing section for attachment with its ash drawer and opening extending either to the left or right.

4. A lower rectangular-sided metal container having an opening in its top and having an opening in one of its side walls provided with a door, a clinker carrying container slidably mounted in said first mentioned container through said door opening and having an upper opening of larger size than the opening in the said first mentioned container, and a supporting unit adapted to be secured to a furnace having a fire door opening comprising a housing substantially triangular in side elevation and having a rear opening adapted to fit over the furnace fire door opening, a bottom opening and a front opening, a door for the front opening to close the same, the said first mentioned container being supported from said housing, the latter door extending diagonally from the first mentioned container upwardly toward the top of the fire door opening.

5. A lower rectangular-sided metal container having an opening in its top and having an opening in one of its side walls provided with a door, a clinker carrying container slidably mounted in said first mentioned container through said door opening and having an upper opening of larger size than the opening in the said first mentioned container, and a supporting unit adapted to be secured to a furnace having a fire door opening comprising a housing substantially triangular in side elevation and having a rear opening adapted to fit over the furnace fire door opening, a bottom opening and a front opening, a door for the front opening to close the same, the said first mentioned container being supported from said housing, the latter door extending diagonally from the first mentioned container upwardly toward the top of the fire door opening, whereby the said latter opening is arranged for full view of clinkers in a fire box of a furnace and for insertion of a clinker tong or the like to lift a clinker out of the fire door opening into said housing, whence it is dropped into said removable container and left for cooling, the assembly of the first mentioned container and housing being suspended from the

fire door opening of the furnace and leaving space between the said first mentioned container and the floor for the parts of a stoker.

6. A furnace installation according to claim 1, in which the overall length of the clinker disposal unit when installed on the fire door frame is such that the unit hangs from said frame free of the floor and spaced from the floor sufficiently to avoid interference with a stoker feed tube, whereby said unit may be used with front fired installations.

7. A furnace installation according to claim 3, in which the upper housing door extends diagonally from a point adjacent the firing door frame at its top to a point adjacent the lower housing section, whereby a clinker tong may be inserted inwardly and downwardly without interference by the upper housing.

8. A furnace installation according to claim 3, in which the upper and lower housings are provided at their bottom and top, respectively, with inwardly extending border flanges surrounding the opening between them, the said flanges being secured together and overhanging the said clinker receiving drawer, to assure the deposit of all parts of the clinkers in said drawer.

9. An attachment for coal fired furnaces having a firing door opening surrounded by a frame with hinge lugs, comprising a clinker disposal unit, said unit being provided with complementary hinge lugs for engagement with a common pintle carried by the door frame hinge lugs to pivotally secure said unit to said frame and enable said unit to be swung away from said opening, and comprising an upper housing section and a lower housing section, the lower housing section being provided with an upper opening communicating with the upper housing section, and the upper housing section being provided with a door on its forward side for access to both the fire door opening and the lower housing section, whereby a clinker or the like may be removed from the furnace and dropped into the lower housing section.

10. A furnace clinker disposal unit assembly comprising a stoker fired furnace provided with a fire door opening having a rectangular frame provided with hinge lugs at one side for receiving a pintle ordinarily supporting the fire door, and

having a keeper at the other side opposite to the hinge lugs for engagement with a fire door latch, the fire door being removed, a clinker disposal unit comprising a member provided at its upper rear end with box-like walls located to engage the fire door opening frame, hinge lugs on one of said box-like walls, and having apertures adapted to register with the apertures of the hinge lugs on the fire door opening frame, a pintle passing through all of the hinge lugs, a latch carried by the opposite box-like wall and located to engage the keeper on the fire door opening frame, said box-like walls having a lower opening in the lowermost of said walls, and a container depending from said box-like walls and communicating with said opening for receiving a clinker which is withdrawn from the fire door opening and dropped into said container, said box-like walls having their rear side opposite to the furnace provided with an opening and a pivoted closure for said opening.

11. A furnace clinker disposal unit assembly comprising a stoker fired furnace provided with a fire door opening having a rectangular frame provided with hinge lugs at one side for receiving a pintle ordinarily supporting the fire door, and

75 a pintle ordinarily supporting the fire door, and

having a keeper at the other side opposite to the hinge lugs for engagement with a fire door latch, the fire door being removed, a clinker disposal unit comprising a member provided at its upper rear end with box-like walls located to engage the fire door opening frame, hinge lugs on one of said box-like walls, and having apertures adapted to register with the apertures of the hinge lugs on the fire door opening frame, a pintle passing through all of the hinge lugs, a latch carried by the opposite box-like wall and located to engage the keeper on the fire door opening frame, said box-like walls having a lower opening in the lowermost of said walls, and a container depending from said box-like walls and communicating with said opening for receiving a clinker which is withdrawn from the fire door opening and dropped into said container, said box-like walls having their rear side opposite to the furnace provided with an opening and a pivoted closure for said opening, the said opening extending diagonally toward the furnace and upward, whereby when the closure is open a standing operator may look into and downwardly into the furnace through the fire door opening, and may insert a straight clinker tong through the diagonal opening and the fire door opening to grasp a clinker located below the door opening.
